(57) **CLAIM**

I claim the ornamental design for a triple clamp for a motorcycle, as shown.

DESCRIPTION

FIG. 1 is a perspective view from slightly above the triple clamp for a motorcycle.

FIG. 2 is a top plan view thereof.

FIG. 3 is a front elevational view thereof; and,

FIG. 4 is a back elevational view thereof.

The portions shown in broken lines form no part of the claimed design.

The heavy dash-dot-dot line represents the bounds of the claimed design and forms no part thereof.

1 Claim, 3 Drawing Sheets

FIG. 1

FIG. 2
